COCKTAIL TABLE

John H. Jordan, Jr., 8211 S. Maryland Ave.,
Chicago, Ill. 60619

Filed Aug. 29, 1969, Ser. No. 18,919

Term of patent 14 years

Int. Cl. D6—01
U.S. Cl. D33—14

FIG. 1.

FIG. 2.

FIG. 3.

FIG. 4.

FIG. 1 is a top plan view of a table showing my design;
FIG. 2 is a front elevation view;

FIG. 3 is a side elevational view taken from the right of FIG. 1; and

FIG. 4 is a side elevational view taken from the left side of FIG. 1.

The rear of the table is essentially the same in appearance as the front thereof.

I claim:

The ornamental design for a cocktail table, as shown and described.
